UNITED STATES PATENT OFFICE.

ALLEN A. BOWSER, OF FORT WAYNE, INDIANA.

DISPENSING APPARATUS.

1,248,606.

Specification of Letters Patent.

Patented Dec. 4, 1917.

Application filed October 15, 1914. Serial No. 866,759.

To all whom it may concern:

Be it known that I, ALLEN A. BOWSER, a citizen of the United States, residing at Fort Wayne, in the county of Allen and State of Indiana, have invented certain new and useful Improvements in Dispensing Apparatus, of which the following is a specification.

This invention relates to apparatus for dispensing liquid and the like, and is particularly designed and adapted for discharging oil or gasoline, the structure being so made that the operating apparatus is accessible when the hood of the casing is raised vertically and is weather-proof for protecting the apparatus when the hood is closed.

Among the objects of the present invention are to provide a new and improved apparatus of this kind in which the casing is horizontally divisible and vertically movable; to provide means for supporting the discharge hose at an elevation above the ordinary height of a receptacle for receiving the oil; and to provide means for automatically draining the hose.

For the attainment of these ends and the accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings, Figure 1 is a view in elevation of an apparatus of the class described showing the casing in its closed position; Fig. 2 is a similar view with the hood of the casing raised to render accessible the operating parts; Fig. 3 is a sectional view of a portion of the casing showing the operating parts within; Fig. 4 is a sectional view of the upper portion of the hood showing the parts within in elevation; Fig. 5 is another view of the interior of the lower portion of the casing showing some of the parts in section; Fig. 6 is another view of the upper portion of the hood of the casing showing some of the parts in section; and Fig. 7 is a sectional plan view on the line 7—7 of Fig. 3.

The present invention relates to apparatus for dispensing liquid from a tank located at a distance, for example, beneath the ground, and the dispensing apparatus

is intended to be used without any other enclosure than the casing itself which is adapted to be locked in a closed position, as illustrated in Fig. 1, when not in use and is provided with a horizontally divisible casing the upper portion of which may be raised, as shown in Fig. 2, to render accessible the dispensing parts, including the discharge hose itself, which, when not in use, is coiled within the apparatus and is entirely enclosed by the hood or upper portion of the casing. Means is also provided for illuminating the apparatus and for providing a signal lamp which moves with the movable portion of the casing, the whole comprising a distinctive design which is easily recognized and distinguished by its construction and design.

Referring more particularly to the present invention, the apparatus as a whole is enclosed in a horizontally divisible casing consisting of a lower casing 10 and a movable upper casing or hood 11. In the preferred construction, the hood is formed with a lower portion of substantially the same diameter as the lower portion 10 of the casing and with an upper extending portion 12 of reduced size. The lower casing 10 is preferably secured to a base 13 which in turn is supported upon the ground or upon any other suitable support and to a top piece 14 above which are certain parts of the apparatus. The hood 11 is designed either to meet the lower casing 10 or the top piece 14 so that a weather-proof inclosure is made for the entire apparatus when the hood is down, and in the top piece 14 is a lock 15 comprising an aperture 16 (see Fig. 7) into which a locking projection 17 (see Fig. 5) extends to be engaged by the lock. This is to prevent unauthorized persons from having access and to lock the casing closed when it is desired.

Within the lower portion of the casing, is a pump cylinder 18 having communication through a valve 19 with a supply pipe 20. This valve 19 admits liquid by the suction of the cylinder 18 and is positively closed by means of a rod 21 when a pump rack 22 and the other dispensing apparatus is in predetermined position. Connected with the cylinder 18 is a filter 23 from which a discharge pipe 24 extends upwardly within the hood 11.

An operating shaft 25 has suitable driv-

110

ing connection with the pump rack 22 to reciprocate it, and a suitable indicator 26, compensator 27, and stops 28 are provided for effecting the operation and stopping of the pump. Pivotedly connected to the operating shaft is a handled crank 29 which folds inwardly to the position shown more clearly in Fig. 7, when the hood is closed and is rotatable to the position shown by dotted outline in this figure for operating. Attached to the crank 29 is a spring-pressed dog 30 which engages a shoulder 31 for holding the crank in operating position. The dog 30 is preferably in the form of a bell crank so that it may be engaged by the finger for compressing its spring and releasing it from engagement with the shoulder 31 when it is desired to fold the handle inwardly.

Attached to the top of the discharge pipe 24 is a discharge head 32 in which is a discharge valve 33, and connected with the discharge head by means of a pipe 34 is a discharge hose 35 preferably flexible and of such a length that it will extend a distance from the apparatus when the hood 11 is raised. At the discharge end the hose is provided with a discharge nozzle 36 for insertion within tanks, receptacles and the like. Connected with the discharge head 32 is a hose draining device 37 which admits air to the discharge head on the discharge side of the valve 33, thereby insuring that all the liquid will drain from the hose so long as the discharge end is not raised above the discharge head 32, or the hose is not looped, and keeping the hose free from liquid when the pump is not in operation. In the ordinary operation of the pump, the valve 33 raises when liquid is discharged, and means is also provided for positively closing the valve 33 when desired, the means comprising a valve stem 38 attached to a pivoted lever 39 which in turn is connected to a rod 40 extending to a pivoted block 41 (see Figs. 3 and 5) controlled by a lever 42. When the lever raises the rod 40, it carries with it the stem 38 which permits the valve to be freely opened by the discharging liquid and to be positively closed when the rod is lowered, a spring 40' being provided at the end of the rod to insure uniform pressure on the valve 33.

Within the reduced portion 12 of the hood 11 and adjacent the top thereof, is a plate 43 supported by means of a rod 44 extending from the discharge head 32. Adjacent the bottom of the reduced portion 12 of the hood is a perforated plate 45 secured to the hood 11 through which extend the various pipes and supports which are located in the reduced portion of the hood. The hood is free to move with respect to the upper plate 43 but the lower plate 45 is secured to the hood, and the upper plate being suitably

held acts as a guide for raising and lowering the hood, the plate 45 in turn being guided by the supports of plate 43. In order to assist in raising and lowering the hood, and to counterbalance it, one end of a spring or a flexible member 46 is secured to the plate 45, and its other end is attached to a spring reel 47 for constituting a counterbalance. Either a spring or a weighted counterbalance is contemplated for assisting in raising the hood 11.

Extending through and secured to the upper plate 43 is a conduit 48 which passes through the lower plate 45 and has a connection 49 through the lower portion of the casing and the base of the apparatus to a suitable source of electrical supply. Also extending through the upper plate 43 and depending therefrom is a conduit 50 with an electric lamp 51 at the lower end thereof for illuminating the operating mechanism below the hood when it is raised, an opening being provided in the lower plate 45 through which the lamp passes when the hood 11 and the plate 45 are raised. A switch 45' is provided which is operated by the hood 11 when it is raised and lowered; the switch controls the circuit of the lamp 51, whereby the lamp is lighted when the hood is raised and extinguished when the hood is lowered and closed.

Supported by the reduced portion 12 of the hood 11, at its upper end, is a casing 52 upon which is supported an electric lamp 53 with a globe 54 inclosing it, the casing 52 being provided with a suitable groove 55 for holding the globe in position. Within the casing 52 and extending from the conduit 48, are insulated electrical conductors 56 and 57 the former of which extends into the conduit 50 for lighting the lamp 51, and the latter of which is coiled within the casing and connected to the lamp 53. This coil is for the purpose of forming a connection with the lamp 53 such that the electrical circuit is not disturbed by the raising or lowering of the hood. For this purpose, side straps 61 are provided, each connected to the coil 51 at a number of points and having loops 62 which are taken up when the coil is extended. This is to keep the coil 57 in place and to prevent it from uncoiling. Thus a visible signal is given at night for distinguishing this dispensing apparatus and for observing it from a distance.

Surrounding the pipe 24 adjacent the bottom and about the conduit 48 adjacent the top, are springs 58 and 59 respectively, which serve as buffers for the hood when it is raised and lowered.

In the ordinary operation, it is necessary only to unlock the hood and to raise it by means of handles 60 provided for that purpose, to uncoil the hose 35, and to move the

handled crank 29 to its operating position whereupon the operating shaft 25 may be rotated to reciprocate the pump rack 22 and operate the pump for any predetermined quantity. During the operation of the pump, the valve 19 is positively closed upon the down stroke of the pump piston.

With this construction, the discharge hose is always drained so that the fluid pumped is not held in the hose causing it to deteriorate.

In closing the apparatus, the hose 35 is coiled in any suitable manner within the casing, the crank 29 is released from its operating position and rotated inwardly, and the hood is moved vertically downward, inclosing the apparatus and opening the switch 45° to cut off the lamp 51.

While I have thus described the preferred construction, combination and arrangement of parts which constitute the present invention, it is obvious that others skilled in the arts to which this appertains, may make various changes without departing from the spirit and scope of the invention.

What I claim is:

1. In liquid dispensing apparatus, the combination of liquid discharging means comprising a foldable operating crank, and a movable casing for entirely inclosing said means, the crank of which is unfoldable to clear the casing when it is moved to uncover the discharging means.

2. In liquid dispensing apparatus, the combination with an inclosing casing a part of which is movable, of liquid discharge means entirely inclosed by the casing when the movable part is closed, the said means comprising a pivoted crank for operating it which is rotatable from a position within the casing to a position clear of the movable part when it is opened.

3. In a liquid dispensing apparatus, the combination with pumping means, of a casing secured to and normally inclosing the said apparatus, having a vertically movable portion of such casing to uncover certain parts of the apparatus for operation, a discharge pipe extending upwardly above that part of the pumping means uncovered in operation, and a flexible discharge hose secured to the upper end of said discharge pipe.

4. Liquid dispensing apparatus comprising liquid pumping means, a casing secured to and inclosing said apparatus comprising a movable portion which has an enlarged portion to directly incase said means and a portion of reduced size, the dispensing apparatus embodying a discharge pipe which extends upwardly beyond the said incasing portion and into the portion of reduced size when the movable portion of the casing is raised or lowered, and a flexible discharge hose securable to the upper end of said discharge pipe.

5. Liquid dispensing apparatus comprising liquid pumping means, a filter connected thereto and an upwardly extending discharge pipe connected to the filter, in combination with a casing for inclosing said apparatus comprising a movable portion with an enlarged portion to directly incase the pumping means when the movable portion is closed, and a portion of reduced size into which the upper end of the discharge pipe extends, the pipe being inclosed by the said reduced portion when the movable portion of the casing is raised or lowered.

6. Liquid dispensing apparatus comprising liquid pumping means, a filter connected thereto and an upwardly extending discharge pipe connected to the filter, in combination with a casing for inclosing said apparatus comprising a movable portion with an enlarged portion to directly incase the pumping means when the movable portion is closed, a portion of reduced size into which the upper end of the discharge pipe extends, the pipe being inclosed by the said reduced portion when the movable portion of the casing is raised or lowered, and a flexible discharge hose connected to the upper end of the discharge pipe and extending downwardly through the reduced portion of the casing and without the enlarged portion thereof when the movable portion of the casing is raised.

7. In a liquid dispensing apparatus, the combination with manually operable pumping means, of a casing secured to and normally inclosing the pumping means having a vertically movable portion to uncover parts of said means for manual operation, and a fixed discharge pipe which extends upwardly a predetermined distance above the pumping means.

8. In liquid dispensing apparatus, the combination with liquid dispensing means including an upwardly extending pipe comprising a support, a hood with a reduced portion inclosing the pipe, a flared portion to cover the discharge means, means to resiliently support the hood for vertical movement, and a discharge hose connected with the upper end of the pipe extending from beneath the hood to discharge liquid from an elevation.

9. Liquid dispensing apparatus comprising liquid pumping means, an upwardly extending discharge pipe, a valve in the discharge pipe, a discharge hose connected to the upper end of the discharge pipe, and an air inlet valve at the top of the discharge pipe to drain only the discharge hose.

10. In liquid dispensing apparatus, the combination with liquid discharge means, of a discharge pipe therefor extending above the height of a receptacle into which it is to discharge, a valve in the pipe adjacent the upper end, a discharge hose connected to the

upper end of the discharge pipe, and an air inlet valve at the upper end of the discharge pipe to cause only the hose to drain clear of liquid at all times.

5 11. In liquid dispensing apparatus, the combination with liquid discharge means embodying a discharge pipe extending above the height of a receptacle into which it is to discharge, a discharge hose connected to the 10 upper end of the pipe, and a vertically movable hood with a portion to inclose the pipe and the hose and with a flared portion at the bottom in which the free end of the hose is inclosed when the hood is in its lowermost 15 position.

12. In liquid dispensing apparatus, the combination with liquid discharge means comprising a discharge hose, and a horizontally divisible inclosing casing for the 20 discharge means, the upper portion of which is movable to render accessible a portion of the discharge means and the discharge hose and is movable to entirely inclose the discharge means and discharge hose.

25 13. In liquid dispensing apparatus, the combination with a horizontally divisible casing, the upper portion of which is movable, of liquid discharge means entirely inclosed by the casing when the portions there- 30 of are joined, comprising a folding crank for operating the discharge mechanism movable from a position within the casing to a position clear of the casing when the upper portion is raised.

35 14. In liquid dispensing apparatus, the combination with liquid discharging means embodying an upwardly extending discharge pipe, a valve at the top of the pipe, and means adjacent the bottom of the pipe connected with the valve for manually operating it.

40 15. In liquid dispensing apparatus, the combination with pumping mechanism embodying a discharge pipe extending above 45 the pumping mechanism to a height above a receptacle into which it is to discharge, an outlet valve at the upper end of the pipe, and means connected with the valve comprising a lever adjacent the pumping means for 50 positively closing the valve.

16. In liquid dispensing apparatus, the combination with a horizontally separable casing, the upper portion of which is movable, of pumping mechanism comprising a 55 rotatable operating member, a foldable crank for said operating member movable from a position where it is inclosed by the upper portion of the casing to a position free from the casing, and a spring-pressed lock for holding the crank in its operating 60 position.

17. In liquid dispensing apparatus, the combination with pumping means embodying a discharge pipe extending above the 65 ordinary height of a receiving receptacle, a

discharge hose connected to the upper end of the discharge pipe, an air inlet valve for draining the discharge hose, a discharge valve at the end of the discharge pipe, and means connected to the latter valve and 70 operable from adjacent the pumping means to positively close the valve.

18. In liquid dispensing apparatus, the combination with pumping mechanism comprising a cylinder, a discharge pipe extending 75 above the cylinder, an inlet connection for the cylinder, a positively closing valve in the inlet connection, a discharge valve at the upper end of the discharge pipe, and means for positively operating the valve at 80 the upper end of the discharge pipe.

19. In liquid dispensing apparatus, the combination with pumping mechanism embodying a discharge pipe extending a distance above the pumping mechanism, an 85 other pipe connected to the discharge pipe at its top, a self-closing valve for the discharge pipe adjacent the top thereof to prevent back flow of liquid in the pipe, and an air inlet valve at the top of the said other 90 pipe to drain it.

20. In liquid dispensing apparatus, the combination with a horizontal separable casing, the upper portion of which is movable, of pumping mechanism comprising a rotatable operating member, and a crank attached to said operating member foldable from a position where it is clear from the casing so that the member may be freely rotated to a position where it is inclosed 100 by the upper portion of the casing when the casing is closed.

21. Liquid dispensing apparatus comprising liquid pumping means, a liquid discharge pipe extending upwardly beyond 105 said means, a casing secured to and inclosing said apparatus having a portion which is vertically slidable to expose said pumping means for manual actuation, and a discharge hose connected to the upper end 110 of said discharge pipe.

22. Liquid dispensing apparatus comprising liquid pumping means and an upwardly extending discharge pipe, in combination with a casing for inclosing said apparatus 115 comprising a vertically slidable portion to directly inclose the apparatus when in one position and to expose the pumping means for manual operation in another position.

23. In liquid dispensing apparatus, the combination with liquid pumping means and a discharge pipe extending above said means, a discharge hose connected to the upper end of the pipe, and a horizontally divisible casing, one portion of which is 120 vertically slidable with respect to the other and movable to expose the liquid pumping means for manual actuation when the said portion is in one position.

24. In a liquid dispensing apparatus, the 130

combination with pumping means supported on a common plane with a receptacle to be filled, of a casing secured to and normally inclosing the pumping means having a vertically movable portion of said casing to uncover certain parts of the means for manual operation from said plane, a discharge pipe extending upwardly above that part of the pumping means uncovered for operation and above a receptacle to be filled, and a flexible discharge hose secured to the up-

per end of the discharge pipe and insertible in a receptacle to be filled.

In testimony whereof I have signed my name to this specification, in the presence ¹⁰ of two subscribing witnesses, on this 8th day of October A. D. 1914.

ALLEN A. BOWSER.
